Primary Examiner—Paula A. Mortimer[57] **CLAIM**

The ornamental design for a cremation urn vault, as shown and described.

DESCRIPTION

FIG. 1 is a front elevational view of a cremation urn vault showing our new design, the right, front, and opposite sides are mirror images;

FIG. 2 is a top plan view of the cremation urn vault of FIG. 1;

FIG. 3 is a bottom plan view of the cremation urn vault of FIG. 1; and,

FIG. 4 is a perspective view of the cremation urn vault of FIG. 1.

In FIGS. 1 through 4, the broken lines showing of portions of the corner structure detail is for illustrative purposes only and forms no part of the claimed design.
